(74) Attorney, Agent, or Firm — Murtha Cullina LLP

(57) **CLAIM**

The ornamental design for a caravan, as shown and described.

DESCRIPTION

1. Caravan

1.1 is a front and left side perspective view of a caravan showing my new design;**1.2** is a left side elevation view thereof;**1.3** is a front elevation view thereof;**1.4** is a right side elevation view thereof;**1.5** is a rear elevation view thereof; and**1.6** is a top plan view thereof.

No protection is sought for features shown in shorter dashed lines. The longer dashed line is the boundary of the claimed design and forms no part thereof. The solid lines in the reproductions show the claimed design.

1 Claim, 6 Drawing Sheets(56)
